UNITED STATES PATENT OFFICE.

JAMES E. RAYBURN, OF WAYNESBORO, TENNESSEE, ASSIGNOR OF ONE-HALF TO
CLAUDE L. BOYD, OF WAYNESBORO, TENNESSEE.

AX.

Application filed October 14, 1922. Serial No. 594,539.

To all whom it may concern:

Be it known that I, JAMES E. RAYBURN, a citizen of the United States of America, residing at Waynesboro, in the county of Wayne and State of Tennessee, have invented certain new and useful Improvements in Axes; and I do hereby declare that the following is a full, clear, concise, and exact description of the invention, such as will enable others skilled in the art to which it appertains to make and use the same.

This invention relates to improvements in axes, having for an object to provide a combination broad and chopping ax which will be especially advantageous for use by woodmen in the hewing of logs during the making of squared timbers, such as cross ties and the like, where it is necessary that relatively right angularly disposed flat faces be formed thereon, that side of the broad ax blade of the tool nearest the timber being so shaped as to permit of the hewing of a log without liability of splintering or irregularly facing the same, while the opposite face of such blade has the so-termed "chip ridge" formed in a manner to cause positive and rapid removal of turning of the chips from the timber.

Another and equally important object of the invention is to provide a tool of the character mentioned embodying in a single construction, the several axes, namely, chopping and broad axes required by a workman when hewing timber, thus dispensing with the need of separate tools and likewise, permitting of immediate selective use of either.

Other objects will be in part obvious and in part pointed out hereinafter.

In order that the invention and its mode of operation may be readily understood by persons skilled in the art, I have in the accompanying illustrative drawings, and in the detailed following description based thereon, set out one possible embodiment of the same.

In these drawings:

Figure 1 is a plan view showing one side of the improved combination ax, that is, that side or face bearing the "chip ridge";

Figure 2 is an end view of the same;

Figure 3 is a plan view of the opposite side or face of the combination ax; and,

Figure 4 is an edge view of the broad ax or blade.

Having more particular reference to the drawings, in connection with which like characters of reference will designate corresponding parts throughout, the improved tool may be stated to comprise a head 1 having the usual handle receiving opening formed therein. Upon one side of this head 1, there is formed a chopping blade 2, while upon the opposite side, a broad blade 3 is formed. By this combining of the several ax blades in a single construction, it will be understood that either of the same may be selectively used as desired by a workman without the necessity of exchange of tools and the incident loss of time as well as the inconvenience caused thereby.

The chopping blade 2 of the improved ax corresponds to those forms of chopping blades now common in the art, having the usual curved cutting edge 4. This blade is of such size as will permit the drawing of metal from the head 1 for forming the same.

The broad blade 3 by reason of the novel shaping or forming of its several faces provides a desirable and effectual device for use in the hewing of timber. That side or face of the blade indicated by the numeral 5, which is the side nearest the timber from which the chips are being hewn has its medial portion slightly concave longitudinally from the point A adjacent the head 1 to the point B in proximity to the cutting edge of the blade, as clearly shown in the Figure 3, so that were a straight edge implement rested upon these points A and B, the intermediate portion thereof would not contact with the corresponding portion of the side 5. The remainder of the blade face is formed substantially flat as is usual in constructing tools of this character.

By reason of the concave construction of the medial portion of the face 5 of the broad blade, that portion of the ax when in use will be prevented from working its way from the timber in such a manner as to render the forming of the flat face upon the timber difficult. To the contrary, because of this concaving, the face 5 of the blade will be caused to move in a substantially parallel-like course over the face of the timber being hewn, thus permitting the forming of the squared or perpendicular faces with the least effort or labor. Likewise, by reason of the

peculiar formation of the face 5 of the blade, the hewing of the timber may be much more quickly accomplished and at the same time, a neater and more uniform surface will be provided.

- The opposite or remaining side indicated by the numeral 6 of the broad blade is provided with what is commonly known in the art as the "chip ridge." This ridge, however, 10 is usually made in form of a sharp or acute extension which extends from the point indicated at C medially and longitudinally of the broad blade to the point indicated at D, whereupon the ridge is divided in the form 15 shown in the Figure 1 and extending in diagonal fashion to the points indicated by the reference letters E and F, which as will be noted, are in proximity to the opposite extremities of the cutting edge of the blade. 20 Instead of forming this substantially wide cutting ridge at a sharp or acute angle, I have found through experience that more practical results are secured when the apex portions of the "chip ridge" are rounded, 25 as for example, as shown in the Figures 1 and 2.

From the foregoing, it is believed that the advantages offered by the use of the combined chopping and broad ax are obvious. 30 However, it will suffice to state that in the use of this combined tool, no appreciable time is lost in changing tools. In the proper hewing of timber or a log which is to be made into squared timbers, such as cross ties, et cetera, having substantially flat right angularly disposed faces, it is first necessary to "score" the timber. This is done by making shallow hacks or indentures with the chopping blade of the ax along the face 40 to be hewn. The hacks are preferably made at right angles to the grain of the wood. The purpose of "hacking" the timber is to prevent the chips from splitting deeper into the wood than is desired, and to cause them 45 to turn from the wood much more readily. It is practically impossible to "score" timber with a broad ax and in consequence, expert woodmen use the ordinary chopping ax for this purpose. Therefore, in the combination tool presented by my invention, 50 both of the essential ax blades required in the hewing of timber of the above character are always convenient to the workmen and

likewise, the expense of an additional or extra tool is avoided. Furthermore, the 55 combined tool will be found highly desirable for use by woodmen when it is necessary to cut limbs, knots, sprouts, et cetera, since the use of a broad ax for this purpose is most detrimental, although to save time, woodmen 60 frequently employ the same with the result that it is frequently broken because of its size and temper. In using the improved tool, it would be only necessary to reverse 65 the positioning of the blades so that the chopping blade 2 could be used by the woodman.

It is to be understood that the broad ax blade may be used alone, that is, without the chopping ax blade or similar form of blade. 70 Thus, a user would be afforded the advantages of the improved broad ax blade formation in those cases where the use of a chopping ax is not desired.

Manifestly, the construction shown is 75 capable of considerable modification and such modification as is within the scope of my claims, I consider within the spirit of my invention.

I claim:

1. A tool of the character described comprising a head, a broad blade on the head, one side of said broad blade having a chip ridge formed thereon extending longitudinally of its medial portion from a point in 80 proximity to said head to a point in proximity to the cutting edge of the blade whereupon it is formed with divergent branches extending to points adjacent the opposite extremities of the cutting edge of said blade. 85

2. A tool of the character described comprising a head, a broad blade formed upon one side of said head, one side of said broad blade having a chip ridge formed thereon, the apex portions of which are rounded, said 90 chip ridge extending longitudinally of the medial portion of said opposite side of the broad blade from a point adjacent said head to a point in proximity to the cutting edge of said blade whereupon it is formed with divergent branches extending to points in 95 proximity to the opposite extremities of the cutting edge of the blade.

In witness whereof I have hereunto set my hand.

JAMES E. RAYBURN.
